UNITED STATES PATENT OFFICE.

AUGUST J. KREUZKAMP, OF CHICAGO, ILLINOIS, ASSIGNOR TO ENGLANDER SPRING BED COMPANY, OF BROOKLYN, NEW YORK, A CORPORATION OF NEW YORK.

BED.

1,418,382.

Specification of Letters Patent. Patented June 6, 1922.

Original application filed June 4, 1921, Serial No. 475,005. Divided and this application filed February 10, 1922. Serial No. 535,458.

To all whom it may concern:

Be it known that I, AUGUST J. KREUZKAMP, a citizen of the United States, residing at Chicago, in the county of Cook and State of Illinois, have invented certain new and useful Improvements in Beds, of which the following is a specification.

This application is a division of my co-pending application for beds, filed June 4, 1921, Serial No. 475,005, an object of the present invention being to provide an improved bed comprised of detachable parts, the mattress section being detachably connected to the head and foot by improved means whereby in detaching the parts it is not necessary to maintain the head or foot in parallel relation with the upright end of the mattress section, thereby greatly facilitating the manipulation of the parts.

A further object of this invention is to provide an improved knockdown bed structure having a head and a foot which comprise each a cross member terminating in depending supporting members and a spring mattress supported therebetween, and provided with an end bar located substantially in alignment with a cross member of the structure, the mattress being detachably connected to the head and foot by means of detachable connections, one thereof comprising a laterally swinging connection extending over the top of the end bar and cross member.

Other objects of this invention will appear in the following description thereof, reference being had to the accompanying drawing forming a part of this specification wherein like reference characters indicate corresponding parts in the several views and wherein Fig. 1 is a perspective view of a bed structure embodying my invention; Fig. 2 is an end elevation partly in section illustrating the same; Fig. 3 is a fragmentary perspective view illustrating certain parts of my improved structure and the manner of connecting the mattress with the foot; Fig. 4 is a detail view in section illustrating the manner of connection of the mattress section and foot; Fig. 5 is a detail view illustrating the manner of connection of the mattress section with the head; and Fig. 6 is a detail view of a laterally swinging hook.

In carrying out my invention, the pre-

ferred form thereof being illustrated in the accompanying drawings, I have provided in 55 general a knockdown bed comprising a head and a foot and a spring mattress section detachably connected thereto in such manner as to permit the parts to be knocked down or assembled easily without the expenditure of 60 great effort and exertion. The main bed section in the present instance comprises a head 9 and a foot 10, each of which in the present instance consists of a main top or cross member terminating at the ends thereof in legs 11. The spring mattress frame comprises a pair of end members 13 to which a spring fabric 24 is connected in the usual manner, and in the present instance each of these end members is shown as formed of 70 angle iron and is provided with depending portions 14 connected by cross members or bars 12. These depending portions 14 at their lower ends are connected by spacing bars 15, preferably constructed of angle iron, 75 which maintain the ends properly spaced apart when the spring fabric is stretched therebetween.

Each of the legs 11 of the head and foot is provided on its inner side at a predetermined 80 distance below the top of the spring with inwardly extending headed pins 32. Each of the depending portions 14 is provided with a notch or slot 33 for the reception of the headed pins 32. The heads 9 at each side 85 is provided at a point adjacent to the top of the spring with a vertically swinging hook 30, pivoted to the inner side of the leg. The foot 10 has the horizontal upper cross member thereof substantially in alignment with 90 the corresponding member 13 of the mattress section, and this cross member, preferably centrally thereof, is provided with a laterally swinging hook 31 so pivoted as to have also a limited or restricted downward 95 swinging movement just sufficient to permit the hooked portion to hook over the end bar 13 and, when detaching the parts, to be lifted to clear the bar so as to be swung laterally out of the way.

It will thus be observed that the detachable mattress section 24, is connected with the head and foot at the bottom thereof by pin and slot connections, and at the top the head 9 is connected to the mattress section 105 by vertically swinging hooks, and the foot

10 is connected to the mattress section by a single horizontally swinging hook 31 having a restricted vertically swinging movement. Said hooks are adapted to hook over the end 5 bars of the mattress section and act to wedge the mattress section into tight engagement with the head and foot, thus preventing any shaking or wobbling joints. In detaching the parts the hooks are released and shifted 10 away from the member 13, before the mattress is handled, and then the head or foot is swung away from the mattress section and the same readily lifted from the pins 32 and lowered to the floor. Thus it is not necessary 15 to maintain the members 14 and 11 in parallel relation in order to disconnect the pin and notch connection, and furthermore this swinging movement of the head and foot tends to loosen the connections, and so 20 there is no possibility of a binding or sticking action when detaching the mattress section.

Thus due to the great ease with which the mattress section may be detached from the 25 head and foot without necessitating the maintenance of the upright members 14 and 11 in parallel relation, and without any binding or sticking of the connecting parts, this detachment may be accomplished with a 30 minimum of effort irrespective of the weight of the various parts. Furthermore, where the cross member of the foot is constructed to be located in use substantially in alignment with the end bar of the mattress section, it is possible to use a single laterally 35 and vertically swinging hook connection which will not only accomplish all of the functions of a plurality of hooks, but will also result in a simplification of construction as well as a simplification in the manipulation of the parts. It has been found therefore in practice that by virtue of the present improved connection between the spring mattress frame and the foot, wherein 40 the laterally swinging hook hooks over the top of the end bar, a substantial saving in time, effort, and labor in the manipulation of the parts results.

I claim as my invention:

50 1. A knockdown bed structure comprising a head and a foot, the latter including a cross member terminating in depending portions, a detachable mattress section therebetween and comprising an end bar adapted to 55 be located in juxtaposition to said cross member, said section being connected with the head by sliding connections at one point and swinging hook connections at another, and connected to the foot by sliding connections, and a laterally swinging hook connection 60 at a point intermediate the ends of the end bar, said last hook connection being carried by the cross member and adapted to hook over the top of said juxtaposed end 65 bar.

2. A knockdown bed structure comprising a head and a foot, the latter including a cross member terminating in depending portions, a detachable mattress section therebetween and comprising an end bar adapted to 70 be located in juxtaposition to said cross member, said section being connected with the head by sliding connections at one point, and swinging hook connections at another, and connected to the foot by sliding connections, and a laterally swinging hook connection adapted to extend over the juxtaposed tops of said end bar and cross member and wedge the mattress into engagement with the head and foot and releasable prior to the 75 sliding connections.

3. A knockdown bed structure comprising a head and a foot, the latter including a cross member terminating in depending portions, a detachable mattress section therebetween and comprising an end bar adapted to 80 be located in juxtaposition to said cross member, said section being connected with the head by sliding connections at one point and swinging hook connections at another, and connected to the foot by sliding connections, and a laterally swinging hook connection adapted to extend over the juxtaposed tops of said end bar and cross member and wedge the mattress into engagement with the head 85 and foot and releasable prior to the sliding connections, said laterally swinging hook having a restricted vertically swinging movement.

4. A knockdown bed structure comprising 90 a head and a foot, comprising each a cross member terminating in depending portions, a spring mattress supported therebetween and having an end bar located substantially in alignment with a cross member, said mattress being detachably connected to the head and foot, one of said connections comprising a laterally swinging connection extending over the top of said bar and cross member.

5. A knockdown bed structure comprising 95 a head and a foot, comprising each a cross member terminating in depending portions, a spring mattress supported therebetween and having an end bar located substantially in alignment with a cross member, said mattress being detachably connected to the head and foot, one of said connections comprising a laterally swinging connection extending over the top of said bar and cross member, said connection being releasable prior to 100 certain of the other connections, and said connection having a combined vertical and lateral swinging movement.

6. A knockdown bed structure comprising 105 a head and a foot including each a transverse member, a mattress section therebetween and comprising a transverse end member adapted to be located in juxtaposition to one of said other transverse members, and means for detachably connecting the mat- 110

tress section with the head and foot, said means including a connection between said juxtaposed transverse members.

7. A knockdown bed structure comprising
5 a head and a foot including each a trans-
verse member, a mattress section therebe-
tween and comprising a transverse end mem-
ber adapted to be located in juxtaposition
to the transverse member of said foot, and
10 means for detachably connecting the mat-
tress section with the head and foot, said
means including a connection between said
juxtaposed transverse members.

8. A knockdown bed structure comprising
15 a head and a foot, and a spring mattress
section supported therebetween, and detach-
able connecting means for detachably con-
necting said mattress to the head and foot,
said means comprising a plurality of swing-
20 ing connections at one end of said mattress
and a single swinging connection at the op-
posite end thereof, said connections forming
a substantially triangular connecting me-
dium adapted to permit the structure to be
25 readily knocked-down and assembled.

9. A knockdown bed structure comprising

a head and a foot including each a trans-
verse member, a mattress section therebe-
tween and comprising a transverse end mem-
ber adapted to be located in juxtaposition 30
to one of said other transverse members, and
means for detachably connecting the mat-
tress section with the head and foot, said
means including a releasable connection ex-
tending between and over the top of said 35
juxtaposed transverse members and effective
to wedge the same together.

10. A knockdown bed structure comprising
ing a head and a foot including each a trans-
verse member, a mattress section therebe-
tween and comprising a transverse end mem-
ber adapted to be located in juxtaposition 40
to the transverse member of said foot, and
means for detachably connecting the mat-
tress section with the head and foot, said 45
means including a releasable connection ex-
tending between and over the top of said
juxtaposed transverse members and effective
to wedge the same together.

Signed at Chicago, Ill., county of Cook, 50
this 6th day of February, 1922.

AUGUST J. KREUZKAMP.
